Atty.

UNITED STATES PATENT OFFICE.

JOHN A. McCACKEN, OF RAHWAY, NEW JERSEY.

SEWING-MACHINE SUPPORT.

1,342,686.

Specification of Letters Patent.

Patented June 8, 1920.

Application filed October 13, 1919. Serial No. 330,417.

To all whom it may concern:

Be it known that I, JOHN A. McCACKEN, a citizen of the United States, and a resident of Evenell, Rahway, county of Union, and State of New Jersey, have invented certain new and useful Improvements in Sewing-Machine Supports, of which the following is a specification.

This invention relates to an improved support for sewing machines, and is of the type that is adapted for use in handkerchief mills and similar establishments where more than one machine is handled by a single operator.

15 I am aware that tables have been made in which one sewing machine is arranged above another, which arrangement has been found to result in reduced output on account of the operator being under the necessity of straightening up and then bending over so frequently as to become exhausted.

20 I am also aware that machines have been arranged on a table with their sewing ends spaced apart the width of the goods to be seamed or sewed, but this arrangement takes up a great deal of room and requires nicety of adjustment and synchronizing.

The present invention is adapted to minimize the space necessary and at the same 30 time to permit a single operator to attend to two machines and keep them continuously supplied with articles, such as handkerchiefs to be hemstitched.

For the purpose of clearly describing this 35 invention it will be referred to as used in hemstitching handkerchiefs, so as to clearly indicate how it is an advantageous installation.

The invention further consists in the disposition of the sewing machines made possible by the construction of the table, and also in the arrangement of details in the construction, all of which will be more fully described hereinafter and finally embodied 45 in the claims.

The invention is illustrated in the accompanying drawings, in which Figure 1 is a top view of a pair of tables made according to my present invention, with two sewing machines illustrated in place on one of the 50 tables. Fig. 2 is an end view of the construction shown in Fig. 1, all the sewing machines being illustrated in position. Fig. 3 is a front view of the construction shown 55 in Fig. 1, with the sewing machines on the rear table being shown in dotted outline.

Fig. 4 is a perspective view showing in detail one means for manipulating the clutch on a sewing machine, and Fig. 5 is a perspective view of the front end of a table 60 with a tablet that is attached thereto, and also showing the hemmer and an attachment to the hemmer which permits of the feeding of the edge of material to be hemstitched, to the sewing machine.

65 It will be evident that one support for two machines can be utilized, but for the purpose of illustrating possibilities of the invention I have shown two of such tables arranged for the complete support, in the 70 illustration these tables being shown as being identical, but, of course, it will be evident that slight changes are possible.

The support consists of a front table 10, which has on one end a side table 11 which 75 projects at an angle from the front of the front table 10 and is preferably arranged at a right angle thereto. When more than one of these table portions or supports are used, they are placed back to back and a trough 80 12 is arranged between them, the whole being supported on standards 13 which are preferably provided with top braces or trusses 14 adjustable on the standards 13 and secured in position by suitable fastening means, such as the bolt 15.

The machines are driven by suitable mechanism or connection from a main shaft 16, preferably supported in suitable bearings 17 on the standards 13. On the front table 10 90 95 is a sewing machine 18, and on the side table 11 is another sewing machine 19, the machine 18 being driven by a belt 20 running from the usual pulley on the machine to a pulley 21 on the shaft 16, and the machine 19, which is at right angles to the machine 18, is driven by a belt 22 which passes from the pulley of the sewing machine under the idlers 23 and around the pulley 24 on the shaft 16.

100 Each machine is provided with the usual clutch mechanism, which is not illustrated in detail in this application, these clutch mechanisms being well known in the art, the machines being provided with arms 25 105 which are provided on the end with an extension 26 having a bar 27 which is actuated by a spring 27^a to normally hold the clutch open or inoperative.

The machines 18 and 19 are provided with 110 starting and stopping mechanisms convenient of access and positive in their opera-

tions, the machine 19 being provided with a device comprising a rocking bar 28 which has one end 29 to engage the bar 27, the other end being rocked by a cam-shaped extension 30 on the pivoted handle 31, the handle being usually underneath the head of the machine and convenient of access, and the disposition of these parts does not provide any extending parts to interfere with the 10 passage of goods that are being operated upon by the sewing machine 18.

In the machine 18, a bar 32, which is more clearly illustrated in Fig. 4, is connected to the arm 25 and also passes through the 15 standard 33 and is secured in a latch 34, which has a nose 35 and a handle 36, the handle 36, when turned, causing the nose 35 to engage the standard 33 and pull the bar 32 so that the extension 26 and the arm 25 20 are swung to cause the clutch 37 of the machine to be thrown into clutching position and the machine operates. The disposition of this starting and stopping mechanism is such as to be within reach of the operator, 25 who is situated approximately at the position illustrated by the seat 38 in Fig. 1.

The sewing or needle end of the machine 18 projects toward the machine 19, and the needle end of the machine 19 projects to 30 ward the front end of the table 11.

To illustrate the convenience of the arrangement set forth in this application I will describe the device as used in the hem-stitching of handkerchiefs. The operator, 35 situated at 38, feeds the goods to the sewing end of the machine 19, and, in the case of handkerchiefs, the goods is fed through until the required distance on one edge has been hemmed, and the piece is then hemmed 40 on a second edge in the machine 18, on its third edge on the machine 19 and on its fourth edge back on the machine 18. An operator proficient in the operation of these machines has both machines in operation 45 almost continuously, since the goods only has to be started in the machine, and while one machine is hemming the edge of a handkerchief the other machine is delivering one and being supplied with another. This alternation of feeding from one machine to 50 the other permits of a large output by a single operator without undue exertion. Furthermore, there is no unnecessary reaching for inaccessible elements that require 55 operation, and I have found that with this table installed alongside of the prior arrangements of machines, this is not only the most comfortable for the operator, but it delivers a much larger output.

60 Four-sided articles are usually started in the machine 19 so that the final operation is on the machine 18 and the goods pass into the trough 12, from which they are removed at intervals.

65 When the machines are used for hem-

stitching I provide the hemmer 39 (see Fig. 5) with a right-angled spring 40, which has a return spring 41 which projects inwardly and has a curved inner end 42 which bears against the under face of the feeding plate 70 43 of the hemmer, so that once the goods are inserted in the hemmer this plate holds the goods up and causes it to be properly and evenly fed to the hemmer.

To provide for the proper tension, a tab- 75 let 44 is preferably placed on the front of each table and opposite the sewing end thereof, this being shown in connection with the machine 18 in Fig. 1, the tablet 44 being inclined so as to more properly support 80 the goods and also to cause a bending of the spring 40, which gives the end 42 of the spring 41 the required tension.

When two table portions are used, as shown in Figs. 1 and 2, the standards 13 85 with their adjustable tops or trusses 14 are supplemented by adjustable supports for the outer ends of the tables 11, which supports comprise rods 45 on which are adjustably arranged the sleeves 46 fastened by the 90 screws 47 and having the arms 48 which support the outer ends of the tables 11. At one end of each set of tables I prefer to put a projecting part 49 which spaces the end of the table 11 from the next adjacent table 95 10 and insures the space 50 being left, so that, if desired, goods of considerable length being passed through the machine 19 can be passed down over the edge of the table 11.

I claim:

1. A sewing machine support comprising a front table and a projecting side table, each table supporting a sewing machine, said sewing machines being positioned to feed sewed articles toward the outer edges 105 of the tables.

2. A sewing machine support comprising a front table, and a projecting side table, and a sewing machine on each table portion, the machine on the side table having its needle 110 end projecting toward the end of said table, and the needle end of the other projecting toward the first machine.

3. A sewing machine support comprising a front table, a side table at an angle to the 115 front table, the tables being at substantially the same level, and a sewing machine on each table, whereby an operator at the angle of the tables can feed fabric to both machines.

4. A sewing machine support comprising a front table, a side table projecting at an angle from the front of the front table, sewing machines on both tables and a second front table and side table, sewing machines on both said second tables, the two front tables being arranged back to back.

5. A sewing machine support comprising tables placed back to back, and a projecting table on the front of each one, said project- 130

ing tables being on opposite ends, all said tables being equipped to support sewing machines.

6. A sewing machine support comprising
5 tables placed back to back, a projecting table on the front of each one, said projecting tables being on opposite ends, and a trough arranged between the main tables, the main tables and projecting tables each being
10 equipped to support a sewing machine.

7. A sewing machine support comprising

tables placed back to back, a projecting table on the front of each one, said projecting tables being on opposite ends, a shaft supported longitudinally under said tables, sewing machines on the main tables and the projecting tables, and driving means connecting the shaft and the sewing machines. 15

In testimony that I claim the foregoing, I have hereto set my hand, this 10th day of 20 October, 1919.

J. A. McCACKEN.
